Attorney

UNITED STATES PATENT OFFICE

JAMES J. SUNDAY, OF DETROIT, MICHIGAN, ASSIGNOR TO JAMES W. KELCH, OF DETROIT, MICHIGAN

HEATER FOR AUTOMOBILES

Application filed February 9, 1926. Serial No. 87,024.

This invention relates generally to heaters for automobiles and consists of certain novel features of construction, combinations and arrangements of parts as will be more fully described and particularly pointed out in the appended claims.

In the accompanying drawing:

Figure 1 is a fragmentary side elevation of an automobile with a heater embodying my invention applied thereto.

Figure 2 is an enlarged fragmentary elevation of the heater with certain parts in section.

Figure 3 is a detail elevation of one of the partitions.

Figure 4 is a top plan view of the air inlet duct.

Figure 5 is a front elevation of the air inlet duct.

Referring now to the drawing, 1 is a heater embodying my invention having concentrically arranged inner and outer shells 2 and 3 respectively. As shown, the inner shell 2 is divided by spaced transversely extending apertured disks or partitions 4 into a series of chambers 5 in which the exhaust gases from the engine are adapted to expand, while the outer shell 3 is closed at its ends and is provided adjacent to said ends, preferably at diametrically opposite sides of the inner shell with inlet and outlet openings 6 and 7 respectively for air. To provide an efficient construction, the partitions 4 are provided with the lateral peripheral flanges 8 that fit snugly against and are rigidly secured to the inner wall of the shell 2, while the closed ends of the outer shell 3 are provided with the laterally extending flanges 9 that fit snugly around and are rigidly secured to the outer wall of the shell 2. Preferably the flanges 8 of the end walls 4 and the flanges 9 of the shell 3 terminate flush with the ends of the shell 2, hence these parts may be secured together along their outer edges by a single welding operation.

In order that the heater may be applied to exhaust conduits of various sizes, the end walls 4 of the inner shell are preferably provided with openings 10 of sufficient area to receive the largest exhaust conduits now in

use. In the present instance, the exhaust gases from the engine are conveyed to the forward end of the inner shell 2 by means of a standard conduit section 11 and are discharged from the rear end of the shell into a standard conduit section 12. Thus, with this arrangement, suitable adapters having openings of various sizes may be employed for holding the conduit sections rigidly in assembled position. As shown, the adapter 13 preferably comprises the cooperating plates 14 and 15 and the resilient gaskets 16. To facilitate assembly, these plates have openings therein for receiving suitable bolts 17, while the gaskets 16 are clamped between the plates 14 and 15 by means of these securing bolts. Inasmuch as these bolts extend outwardly through the end walls 4 it is apparent that the adapter plates 13 may be easily and quickly applied to or removed from the heater. In this connection it will be noted that the bolts 17 are prevented from falling or being pushed inside the heater when the adapter plates are applied by means of the rearwardly converging walls of a perforated cone 18 that is preferably rigidly secured to the rear face of the forward wall 4. As shown, this cone 18 is directly in rear of the exhaust conduit section 11, hence will also serve effectively to break up the exhaust gases into small particles and to deflect the same laterally within the first expansion chamber 5.

Air from the atmosphere is supplied to the inlet opening 6 in the shell 3 by a suitable duct 19 and after being heated by the exhaust gases in the chambers 5 is discharged into a suitable conduit 20 which leads from the outlet opening 7 to a suitable register 20' in the floor of the vehicle body. As shown, the duct 19 is provided at its forward end with an outwardly flaring portion 21 and is provided intermediate its ends with the upwardly extending longitudinally curved top wall 22. Located within this duct, preferably below the curved top wall 22, is a baffle 23 that preferably extends upwardly from the bottom wall of the duct to a point in substantial alignment with the upper wall 24 at the rear end of the duct. Thus with this construction water, dust and foreign matter

of any kind entering the duct through its flared forward end will be effectively prevented by the baffle 23 from passing into the heater shell 3. In this connection it will be noted that the bottom wall 25 inclines downwardly from the baffle 23 to the forward end of the duct, hence fluids stopped by the baffle 23 will be discharged from the duct by draining down the inclined bottom 25. If desired, a small port or opening (not shown) may be provided in the bottom wall 25 adjacent to the baffle to permit the escape of such foreign matter.

To facilitate the attachment of the heater to an automobile, the air conduit 20 is preferably swiveled in the outlet opening 7 in the outer shell, hence this conduit may be readily adjusted to a convenient position for attachment to the register in the floor of the automobile body.

Thus, from the foregoing description, it will be apparent that the apertures in the cone 18 and partitions 4 will permit the exhaust gases to flow freely through the shell 2, hence these parts will serve effectively to deaden the sound of the engine exhaust without causing objectionable back pressure on the engine. It will also be apparent that the tubular shell 2 will receive the heat thrown off by the gases flowing through the chambers 5 and therefore will provide a large heating surface for the air within the outer shell 3. Thus, this construction serves efficiently as a combined heater and muffler.

While it is believed that from the foregoing description, the nature and advantage of my invention will be readily apparent, I desire to have it understood that I do not limit myself to what is herein shown and described and that such changes may be resorted to when desired as fall within the scope of what is claimed.

What I claim as my invention is:

1. A heater for automobiles including a chamber for exhaust gases having an opening therein, an adapter for exhaust conduits having an opening in alignment with the opening in said chamber, means for detachably securing said adapter to said chamber including headed elements projecting outwardly from said chamber, and a deflector for said gases upon the inside of said chamber forming a receptacle surrounding the headed elements for preventing said securing means from falling or being pushed inside the chamber when the adapter is being adjusted.

2. A heater for automobiles including an inner shell constituting a muffler casing provided with end walls having longitudinally extending peripheral flanges secured to the inner wall of said shell and terminating flush therewith, an outer shell surrounding said inner shell and spaced therefrom to form an air chamber and provided with lateral in-turned flanges contacting with the outer wall

of said inner shell, and longitudinally extending flanges projecting from said lateral flanges and terminating substantially flush with the end portions of the outer wall of the inner shell and with the peripheral flanges of the end walls of the inner shell, the said flanges and end portions being secured together by a weld.

In testimony whereof I affix my signature.

JAMES J. SUNDAY.
